DOUBLE BAR LOCK

Richard D. Babcock, Massapequa, N.Y., Melvin A. Gervis, Haworth, and Eugene Taras Wozny, Harrington Park, N.J., and Nicholas Giardina, Mount Vernon, N.Y., assignors to Magic Eye Associates, Inc., New York, N.Y.

Original design application May 21, 1971, Ser. No. 146,000. Divided and this application Apr. 19, 1972, Ser. No. 245,709

Term of patent 14 years

Int. Cl. D8—07

U.S. Cl. D8—117

FIG. 1 is a front plan view of the double bar lock showing our new design;

FIG. 2 is a top plan view thereof;

FIG. 3 is a bottom plan view thereof;

FIG. 4 is a rear plan view thereof;

FIG. 5 is a side elevational view thereof;

FIG. 6 is a front plan view of a second embodiment of the double bar lock of our new design;

FIG. 7 is a top plan view of the embodiment of FIG. 6;

FIG. 8 is a bottom plan view of the embodiment of FIG. 6;

FIG. 9 is a rear plan view of the embodiment of FIG. 6; and

FIG. 10 is a side elevational view of the embodiment of FIG. 6.

This is a division of application Ser. No. D. 146,000, filed May 21, 1971, entitled, "Double Bar Lock."

We claim:

The ornamental design for a double bar lock, substantially as shown and described.
